UNITED STATES PATENT OFFICE.

EDWIN E. BARNEY, OF NEW ROCHELLE, NEW YORK, ASSIGNOR TO REMINGTON TYPE-WRITER COMPANY, OF ILION, NEW YORK, A CORPORATION OF NEW YORK.

TYPEWRITING MACHINE.

Application filed July 20, 1923. Serial No. 652,683.

My invention relates to line lock, space key and case shift mechanisms for typewriting machines, and its chief object is to provide new and improved mechanisms of the 5 character specified.

To the above and other ends which will hereinafter appear, my invention consists in the features of construction, combinations of devices and arrangements of parts herein- 10 after described and particularly pointed out in the claims.

My invention is herein shown as applied to the newly marketed machine known as the Smith premier No. 60 typewriter,

15 Figure 1 of the drawings being a fragmentary front-to-rear vertical sectional view of one of said machines embodying my invention, only so much of the machine being shown as is necessary to a full understand- 20 ing of the invention.

Figure 2 is a fragmentary vertical sectional view taken on a plane indicated by the section line 1—1 in Fig. 1.

Figure 3 is a transverse vertical sectional view taken on a plane designated by the section line 2—2 in Fig. 1 and looking in the direction of the arrows at said line.

Figures 4 and 5 are fragmentary views of certain of the line lock devices.

30 The main frame of the machine comprises a rectangular base portion 1 from which rise posts 2 supporting a top plate 3. From the top plate rise goose-neck brackets 4 to which are secured fixed track bars or guide rails 5 and 6 that are oppositely grooved and co-operate through anti-friction rollers 7 with the oppositely grooved top and bottom portions of a rear bar 8 that is part of a traveling carriage. Said carriage fur- 35 ther includes end bars 9 that extend forward from the end portions of the rear bar 8 and support a rotary platen or cylinder 10. The platen carrier or carriage 8, 9 is constantly urged leftward by a motor or spring drum (not shown), such movements being controlled by carriage feeding devices or escapement mechanism comprising a toothed escapement wheel which is fragmentarily shown in Fig. 1 and designated by the num- 45 eral 11. Co-operative with said escapement wheel are escapement dogs 12 and 13 mounted at the top of the upright arm 14 of a dog rocker pivoted at 15 and having a forwardly extending horizontally disposed

55 arm 16, said dog rocker being actuated as hereinafter described from the type bars and the space bar of the machine.

56 The set of type bars 17 are horizontally disposed, being arranged in the arc of a circle below and somewhat forward of the 60 platen 10. They have a common pivot wire 18 mounted on a vertical type bar support or segment 19 which is shiftable to change case as hereinafter described. Each type bar is connected at its heel by a rearwardly ex- 65 tends link 20 with the upright arm of an angular sublever 21 which is pivotally sup- 70 ported on a key lever (not shown) and co- 75 operates with a fixed abutment or cross rod supported in the base 1. When any print- 80 ing key is actuated it is effective through the described train of connections comprising its sublever 21 and link 20 to actuate the connected type bar 17, causing it to swing upward and rearward on its pivot 18 to 85 co-act with the front face of the platen 10. Each type bar is provided with a lower case 90 type and an upper case type, and when the parts are related as in Fig. 1 the inner or lower case type of the type bar will co-act with the platen.

95 Means are provided for shifting the type bar support or segment 19 to change case, 100 said segment in the present instance being shifted downward to change from lower to upper case. To this end the segment is 105 shiftably mounted, being provided at its right and left-hand sides with grooved track ways 22 which co-operate with anti- 110 friction rollers 23, said rollers likewise co- 115 operating with stationary grooved ways in upright guide posts 24 secured to the base 1. Stop devices are provided for limiting 120 the up and down movements of the segment on the guide posts, said stop devices comprising stop lugs 25 and 26 on the segment and 125 co-operating stop arms 27 and 28 mounted on the posts. It will be understood that there 130 are sets of these stop devices at both sides of the segment. Normally the segment is 135 maintained in the Figs. 1-2 position with the stops 26 and 28 contactively engaged by means comprising a coiled spring 29 which 140 is connected with the segment as presently to be described and at its rear end is anchored to a screw hook 30 adjustably mounted on the protruding head portion 31 of a screw which further comprises a shank or

pivot portion 32, said screw being supported on parallel ears 33 comprised in an angular bracket 34 which further comprises a vertically extending comb portion 35, the bracket being secured by screws 35^a to a boss 1^a on the under side of the roof portion of the base 1. The slots in the comb plate 35 receive and guide the rear end portions of two shift levers 36 and 37 which are pivotally mounted on the shank 32 and are maintained in normal position, Fig. 1, by springs 38. The shift key lever 36 is provided with a lock (not shown herein) and the shift key lever 37, which is duplicated at the right-hand side of the machine, is employed for temporary shifts. Both levers 36 and 37 co-operate with a roller 39 that is mounted on a screw pivot 40 carried by the free end portion of a crank arm 41 that extends rearward from a rock shaft 42 mounted on pivots 42^a secured in the sides of the base 1. The crank arm 41 is of sheet metal and fits loosely over the rock shaft 42 but is secured by a screw 43 to a cast metal crank arm 44 of considerable thickness that is fixed to the shaft 42 by a cross pin 45. The cross pin projects downward and is formed with a groove over which the forward end portion of the spring 29 is looped. It will be understood that the described construction of the roller 39 and the crank arms 41 and 44 and the spring 29 is duplicated at the opposite side of the machine. Fixed to the rock shaft 42 inside each crank arm 44 is a crank arm 46 having a hub 47 which fits over the rock shaft 42 and is secured thereto as by a cross pin. The rear end portion of the crank arm 46 has pivotally connected to it at 48 the lower end of a shift link 49, the upper end of which is pivoted at 50 to a lug 19^a on the segment 19. There are two shift links 49, one at each side, and two crank arms 46. The construction is such that when one of the shifting key levers, as the left-hand lever 37, is depressed, it will press down the underlying roller 39 lowering the crank arms 41 and 44 and rocking the shaft 42 which will in turn swing down the crank arms 46 causing the latter through the links 49 to shift the segment downward, the movement continuing until the segment is arrested by the engagement of the stops 25 with the frame stops 27. With the segment in this lower position, the upper case types on the type bars 17 will print when actuated.

The escapement devices are operated directly from the type bars 17 through means comprising a curved universal bar 51 which is arranged in a groove 52 cut in the rear of the segment 19, said universal bar carrying a guide pin 53 which fits loosely in a hole 54 in the segment. Integral with the universal bar 51 and extending rearward therefrom at its opposite side portions are

arms 55 which fit into the forked rear ends of crank arms 56 and are pivotally connected thereto at 57. Said crank arms are fixed to and extend upward from a rock shaft 58 which takes bearings in a bracket 59 secured at the rear of the segment 19 and shiftable therewith. A short crank arm 60 rises from the rock shaft 58 at about its middle, said crank arm carrying a pin 61 which is engaged by the slotted or forked end of a push link 62, said link being also forked at its rear to engage with a headed pin 63 that extends laterally from an arm 64 secured to the upright arm 14 of the dog rocker. The construction is such that when one of the type bars 17 is actuated a nose portion 17^a near its pivot will contact, as the type bar nears the end of its printing stroke, with the universal bar 51, moving said bar rearward, this movement being transmitted to the rocking frame or oscillator comprising the arms 56, rock shaft 58 and arm 60, the latter pushing the link 62 rearward and actuating the dog rocker. When thus actuated the upper arm 14 of said rocker will swing forward disengaging the dog 12 and engaging the dog 13 with the escapement wheel. The return movement of the dog rocker and the completion of the escapement operation is effected by the dog rocker restoring spring 65 which is arranged between the arm 14 and the dog rocker bracket 66. A stop screw 67 carried by the arm 14 limits movement of the rocker by contacting with the bracket 66. It will be observed that the universal bar 51 is operated directly by the type bars to actuate the escapement mechanism during printing operations through a train of connections comprising the described rocker frame and the link 62.

A separate train of connections is employed for actuating the escapement mechanism from the space bar of the machine, said space bar 68 being carried by a pair of spacing levers 69 which are necked to fit over and bear on the rock shaft 42. The levers 69 terminate a short distance back of said rock shaft and are connected by a cross rod 70 which has fixed to it a crank arm 71 carrying an adjustable contact screw 72 that co-operates with a horizontal lip portion 73 extending over the point of the screw from a lever member 74 that is pivoted or fulcrumed at 75 to a lever 76 included in the ribbon vibrating mechanism, said lever 76 having a stationary fulcrum 77. Pivots connected at 78 to the rear arm of the lever 74 is the lower end of a link 79 which extends upward and terminates in a lip 80 overlying the dog rocker arm 16. The upper end portion of the link 79 is provided with a slot 81 which co-operates with a pin 82 on the rocker arm 16. A spring 83 anchored to said pin is connected at its lower end to a pin 84 on the link 79 and tends constantly to move said

link upward. The construction is such that when the space bar 68 is depressed the contact screw 72 carried by the cross rod 70 will be raised, and acting against the lip 73 will 5 rock the lever 74 and lower the link 79, causing its lip 80 to actuate the dog rocker 14—16 and operate the escapement independently of the universal bar 51 and its supporting or rocking frame, these parts remaining motionless by reason of the loose 10 connection afforded by the forked or slotted link 62. Stops are provided for the space bar mechanism comprising a metal arm 85 secured to the under side of the space bar 68 and supporting a pad 86 which normally co- 15 operates with the front portion of the base 1 to maintain the space bar in normal position. The downward limit of movement is determined by a stop pad 87 mounted on 20 an arm or bracket 87^a secured to the base 1 of the machine.

The line lock mechanism is operated by contact devices which in the present case are mounted on the frame of the machine being 25 supported on a toothed bar 88 which is arranged above the upper track bar 6 and has its ends pivotally supported at 89. Adjustably arranged on the stop bar 88 are a number of contact devices or stops including one 30 numbered 90 which is provided with two contacts or projecting lugs 91 and 92, the contact 91 being effective to operate the bell ringing mechanism not herein shown, the other contact 92 actuating the line lock 35 mechanism. Mounted adjustably on said stop bar 88 to the left of the device 90 is a contact device or stop member 93 provided with a lug or stop proper 94 which co-operates with the line lock mechanism to provide 40 a final stop for the line. There may be also provided a stop member 95 having a stop lug 96 and secured by screws 97 to the front of the track bar 6, which lug 96 is effective to prevent accidental displacement of the carriage 45 from its trackways in co-operation with the upstanding stop 98 secured to the front of the carriage bar 8 by screws 99. Integral with the stop 98 is a stop 100 which co-operates with an oppositely disposed stop 50 lug 101 on the carriage to limit movements of the carriage carried line lock contact or stop member. Said member in the present instance is in the form of a bell crank 102 having an upstanding arm 103 and a rightwardly extending horizontally disposed arm 104 terminating in a rearward projection or lip 105. The bell crank lever 102 is carried by a shouldered screw 106 which bears in a boss or projection 107 on the carriage bar 8. 55 The shoulder screw 106 passes in from the back, and its threaded shank projects forward out of the boss 107, the bell crank 102 being screwed or threaded on the shank and abutting against the shoulder of the screw so 60 that the screw and bell crank are rigidly connected thus providing for the bell crank a rigid pivotal extension. The upright arm 103 of the bell crank is confined loosely between the lugs or stops 100 and 101, these parts limiting the pivotal movements of the bell crank which is normally maintained 70 against the stop 100 by a spring 108 that is coiled around the boss or hub 107, one of the ends of said spring engaging the upright arm 103 of the bell crank and urging it 75 constantly leftward. The upper end or tip portion 103^a of the arm 103 has a path of movement which is intersected or crossed by the projections or contacts 91, 92 and 94, so that these contacts are effective during 80 the carriage travel to turn the bell crank on its pivot and throw the arm 104 downward. The back faces of the contacts 91 and 92 are beveled so that during return movements of the carriage should the bell 85 crank arm 103 start from a position at the left of these contacts it will engage with their beveled faces in succession camming them upward and turning the bar 88 on its pivots so that the movement of the carriage 90 will not be obstructed.

The extension 105 of the bell crank as it travels back and forth with the carriage constantly overlies the upper edge of a bar or bail 109 that is arranged in front of and 95 parallel with the lower track bar 5, said bail having at its ends rearwardly extending end portions which receive pivot screws 111 that are threaded into the ends of the track bar 5 and serve as pivots for the bail or bar. 100 A leaf spring 112 secured to the left-hand side of the top plate by screws 113 engages at its free end with the under side of the bar 109 to maintain it in normal position and restore it after actuation. As clearly appears 105 from Fig. 1, the upper edge of the bar 109 lies beneath but out of contact with the contact portion 105 of the bell crank 102 so that these parts do not generate friction during traveling movements of the carriage. 110 Near its middle the bar 109 is formed with a rearwardly bent lug or finger 114 which engages with a line locking device in the form of a hook member 115 that is pivoted on a shoulder screw 116 threaded into the front 115 face of the track bar 5, the hook member being arranged between the track bar and the bail or bar 109. Said hook or member 115 is provided to the left of its pivot or stationary mounting 116 with an extension or 120 finger 117 which overlies the lug 114 on the bail and is normally held up or sustained thereby so as to maintain the hook member in the inclined position illustrated in Fig. 3. The lower end of said member terminates 125 in a hook or engaging portion proper 118 and when in the inclined position, said hook 118 is held out of use or inoperative. When released, the member 115 swings through the force of gravity rightward about the 130

pivot 116 to render the hook 118 operative. Said hook is adapted to co-act with devices on the two trains connecting the escapement dog rocker respectively with the universal bar 51 and the space bar 68. Projecting rearward from the rock shaft 58 is a crank arm 119, said arm being rigid with said rock shaft and providing a support for a second arm 120 terminating at the rear 10 in a head or enlargement 121 formed with an opening or rectangular slot 122. The arm 120 is pivotally supported by a screw pivot 123 on the arm 119 and is held in rigid relationship with said arm 119 by a clamping 15 screw 124 which engages in a slotway 125 formed in the forward portion of the arm 120, the slot affording a limited adjustment or movement of the arm 120 on the pivot 123. The construction is such that when the 20 screws 123 and 124 are loosened, the relationship between the arms 119 and 120 may be varied by turning the arm 120 on its pivot 123 to desired position and thereafter tightening the two screws. By this means a close 25 and exact relationship between the hook 118 and the arm 120 is obtained. The hook 118 likewise co-operates with a device on the link 79, said device being in the form of a T-shaped member comprising a body portion 30 126 from which projects rearward a finger or extension 127. The body portion 126 is formed with a vertical slot 128 which receives a headed clamping screw 129 that is threaded into the link 79. When the screw 35 is loosened the finger 127 may be adjusted up and down to the extent of the slot 128 and thus positioned properly to co-operate with the line locking hook 115, 118.

In operation, assuming that the contact or 40 stop members 90 and 93 have been properly adjusted to arrest the carriage at predetermined points and lock the line, determining the temporary and permanent ends of the line of writing, it will be understood that as 45 the carriage travels towards the left, the tip portion 103^a of the bell crank 102 will co-operate with the contact 91 to ring the bell, after which said tip portion or contact 103^a will engage with the contact 92. The bell 50 crank 102 as a consequence is swung on its pivot until the arm 103 is arrested by the stop 101, thus resulting in the arrest of the carriage, the arm 103 being clamped or confined between the stops 92 and 101. As the 55 bell crank 102 is swung on its pivot by the contact 92, the extension 105 moving downward will engage with the bar 109, swinging said bar downward on its pivots and causing the finger 114 moving downward to release the finger or extension 117 and permit the hook member 115 through the force of gravity to swing rightward about the pivotal center 116 until the hook 118 underlies both the bottom edge of the head 121 and the bottom edge of the finger 127, as illustrated

in Fig. 4. With the parts in this relationship, should one of the printing keys be depressed, throwing the associate type bar 17 towards the printing point, said type bar will engage with the universal bar 51 and tend to move the latter rearward, without effect however, since the universal bar is locked. In other words, the movement of the universal bar will be prevented at this time by the hook 118, said hook preventing the arm 120 and its supporting arm 119 from swinging downward, thereby locking the shaft 58 from rocking and the crank arms 56 and 60 from swinging rearward. Thus the pivots 57 are held or locked, preventing 70 operation of the universal bar and of the type bars, so that the link 62 can receive no motion from the pin 61 and the escapement 80 is not operated. At the same time the finger 127 is prevented from being depressed by the hook 118 thus preventing lowering of the link 79, as well as rocking of the lever 74 and actuation of the space bar levers 69, the space bar 68 being locked as a consequence. 85

One advantage of the present construction is that accent or dead key type bars may be operated while the line is locked as described. An accent type bar is illustrated in Fig. 1 and numbered 17^a, this type bar differing from the ordinary type bar in that it has no contact face or nose 17^a to engage with and actuate the universal bar, this portion of the accent type bar being cut away. As a consequence the accent type bar 95 may be thrown into actuating position without contacting with the universal bar 51, so that even though the universal bar be locked, it will not prevent actuation and printing of the accent type bar. 100

The line locking devices and the carriage may be released by swinging the stop bar 88 on its pivots and releasing the lever 102 and the line lock devices to permit the carriage to advance under actuation of the 110 printing and space keys until finally arrested.

Provision has been made for assuring the effectiveness of the line locking mechanism should the type bars be in shifted or 115 upper case position when the line locking lever 102 is operated as has been described. It will be understood that when the type bar segment 19 is shifted downward for upper case, the universal bar and the rocking frame 120 comprising the shaft 58 will be correspondingly shifted downward and that said shaft will carry downward with it the arms 119 and 120. With the arm 120 in its down-most or shifted position the opening 122 will 125 be brought opposite the locking hook 118, so that when the line lock is actuated the hook, instead of co-acting with the bottom edge of the head 121 as before, will engage with the top edge 122^a of the opening 122 130

passing into the opening for this purpose. Thus the arm 120 is effectively locked against operation, as will clearly be understood from Fig. 5, which shows the parts in effective engagement when the segment is in shifted position.

- Another advantage arises from the described construction in that when the line is locked the shift mechanism is also locked so that the type bar segment is prevented from being shifted when the line locking mechanism is in operation. This is true for both shift positions of the machine, and is due of course to the fact that the part or arm 120-122 which is shiftable bodily with the segment is locked against such movement by the hook 118. With the parts in lower case position and the line locked, the hook 118 underlies the bottom edge of the head 121 thus preventing the arm 120 and the segment 19 from being shifted downward should one of the shift keys be depressed. On the other hand when the segment is down in its upper case position and the line is locked, the hook 118 will be engaged in the opening 122 and the lower edge of said opening abutting against the under edge of the hook will prevent the return shifting movement to lower case position.
- 50 Certain features of invention herein disclosed are not claimed, as they constitute in part the subject-matter of my application, Sr. No. 659,116, filed Aug. 24, 1923.

Various changes may be made without departing from my invention.

What I claim as new and desire to secure by Letters Patent, is:—

1. In a typewriting machine, the combination of a traveling carriage, a platen on said carriage, a contact on said carriage, a co-operating contact having a stationary mounting, a set of shiftable type bars, a universal bar operative by said type bars, an arm connected to said universal bar, said universal bar and said arm being shiftable with said type bars, and a line locking device having a stationary mounting and rendered effective by the coaction of said contacts, said device engaging with said arm in both of the shift positions of said arm.
2. In a typewriting machine, the combination of a traveling carriage, a platen on said carriage, a contact on said carriage, a co-operating contact having a stationary mounting, a set of shiftable type bars, a universal bar operative by said type bars, a rocking arm actuated by said universal bar, said universal bar and said rocking arm shifting with said type bars, and a line lock hook thrown into the path of said arm by the co-operation of said contacts, said hook engaging operatively with said arm in both of its shift positions.
3. In a typewriting machine, the combination of a traveling carriage, a platen there-

on, a contact on the machine frame, an angular lever mounted on the carriage and co-operative with said contact, a bail adapted to be actuated by said angular lever, a line locking member loosely connected to said bail, a set of key operated type bars, a universal bar directly actuated by said type bars, and a rocking arm actuated by said universal bar and with which said line locking member co-acts to prevent the type bars from being actuated.

4. In a typewriting machine, the combination of a traveling carriage, a platen on said carriage, a contact on the frame of the machine, an angular lever on the carriage co-operative with said contact, a bail controlled by said lever, a line locking hook loosely connected to said bail, a set of key operated type bars, a universal bar operative directly by said type bars, and a rocking arm actuated by said universal bar and with which said hook co-acts to prevent the actuation of said type bars.

5. In a typewriting machine, the combination of a traveling carriage, a platen thereon, co-operative contacts one on the carriage and one on the frame, a type bar operated universal bar, a rock shaft connected therewith, an arm fixed to said rock shaft, a second arm pivoted on said first arm and having a set relation therewith, means for affording variation in the normal relation between said arms, and a line locking hook rendered effective by said contacts to engage with and lock said second arm.

6. In line locking mechanism for a typewriting machine, the combination of a locking hook rendered effective by the traveling carriage, means for preventing operation of the type bars of the machine comprising an arm, and means comprising another arm for preventing operation of the space bar of the machine, said line locking hook co-acting directly with both of said arms.

7. In a typewriting machine, the combination of a traveling carriage, a platen on said carriage, a contact on said carriage, a co-operating contact on the frame, a key-operated universal bar, an arm connected therewith, a space bar, escapement devices, connections between said space bar and said escapement devices, another arm carried by said connections, and a line locking hook operative by the co-action of said contacts to engage with both of said arms.

8. In a typewriting machine, the combination of a traveling carriage, a platen thereon, co-operating line lock contacts one being on said carriage, a set of key operated type bars, a dog rocker, a universal bar operative directly by said type bars, connections between said universal bar and said dog rocker, an arm on said connections, a space bar, connections between said space bar and said dog rocker, a second arm carried by said last re-

cited connections, and a line locking hook operative by said contacts to lock both of said arms.

9. In a typewriting machine, the combination of a shiftable type bar segment; key operated means for shifting said segment comprising a rock shaft, a crank arm thereon, and links connected to said segment; escapement devices; a space bar; and connections between said space bar and said escapement devices, said connections comprising a pair of spacing levers supporting said space bar and in turn supported by said rock shaft, a cross bar connecting said spacing levers, a third lever, and a device supported on said cross bar for actuating said third lever.

10. In a typewriting machine, the combination of a shiftable type bar segment, key operated means for shifting said segment comprising a rock shaft, escapement devices, a space bar, a pair of spacing levers supporting said space bar and in turn supported by said rock shaft, a cross bar connecting said spacing levers, an arm on said cross bar, an adjustable contact screw carried by said arm, a third lever having a movable fulcrum and provided with a contact face with which said contact screw co-operates, and a link connecting said third lever with said escapement devices.

11. In a typewriting machine, the combination of case shifting mechanism and line locking mechanism, the line locking mechanism being rendered automatically effective to prevent the operation of said case shifting mechanism.

12. In a typewriting machine, the combination of a shiftable type bar segment, type bars on said segment, key operated means

for shifting said segment, and line locking mechanism automatically rendered effective to prevent the operation of said type bars, said line lock mechanism also being effective to prevent the operation of the means for shifting said segment.

13. In a typewriting machine, the combination of a traveling carriage, a platen thereon, co-operating contacts, one on the carriage, a shiftable segment, type bars on said segment, a universal bar operative by said type bars, a rocking arm actuated by said universal bar, said bar and said arm shifting with said segment, and a line lock hook thrown into the path of said arm by the co-operation of said contacts, said hook preventing the actuation of said universal bar and the shifting of said segment.

14. In a typewriting machine, the combination of a traveling carriage, a platen thereon, line lock contacts one on said carriage shiftable, type bars, a universal bar operative by said type bars, a line lock hook, a device shiftable with said type bars and connected to said universal bar and engageable by said hook, said device having two contact faces, said hook being thrown into the path of said device by the co-operation of said contacts and thereby locking said universal bar, said hook engaging one contact face of said device before the type bars are shifted and being adapted to engage the other contact face of said device when said device and the type bars are in shifted position.

Signed at the borough of Manhattan, city of New York, in the county of New York and State of New York, this 18th day of July, A. D. 1923.

EDWIN E. BARNEY.
